United States Patent

Des. 242,519
Patented Nov. 30, 1976

242,519

FOOT HOE

Leon E. Garrison, 1309 Belaire Drive,
Richardson, Tex. 75080

Filed June 21, 1974, Ser. No. 481,484

Term of patent 14 years

Int. Cl. D8—01

U.S. Cl. D8—11

FIG. 1

FIG. 2

FIG. 3

FIG. 4

FIG. 1 is a perspective view of a foot hoe embodying my new design;

FIG. 2 is a top view thereof;

FIG. 3 is an elevational view thereof; and

FIG. 4 is a perspective view of the foot hoe, with a shoe shown in broken lines for illustrative purposes only.

I claim:

The ornamental design for a foot hoe, as shown and described.
